BALLBASE SHUTTLE TIP

Hector Pavia, Allentown, Pa.

Application May 10, 1947, Serial No. 747,161

5 Claims. (Cl. 139—196)

1

My invention relates to an improvement in shuttle tips and, more particularly, to a ball base shuttle tip that has many advantages over the conventional tips presently in use.

My principal objective was to design a shuttle tip that would prevent any tearing of the filaments or thread as the shuttle moves through the warp. Today, in the weaving industry, due to the use of fine and delicate threads, it is necessary to have a shuttle tip construction that will maintain a smooth joint where the metal tip is affixed to the wooden body of the shuttle. The conventional shuttle body, within a short period of time, becomes frayed and roughened at the point where the tip is affixed to the shuttle body, requiring extensive maintenance to keep the surface of this joint smooth in order that it will not tear the threads of the warp.

Through the use of my improved shuttle tip, it is impossible for any rough edges to form thereby not only saving considerable time and labor in maintenance, but what is more important, extensive tests have shown that this new shuttle tip will stand up under any conditions and can be used indefinitely in the weaving of the most delicate type of cloth without injuring the warp threads.

Further advantages and unique features of my device will be apparent as I proceed with the description.

With reference to the drawings—

Fig. 1 shows a partial plan view of one end of a shuttle using my improved shuttle tip;

Fig. 2 shows a plan sectional view of the end of a shuttle showing my improved shuttle tip affixed to the shuttle body;

Fig. 3 shows a view similar to Fig. 2 showing a modification of my invention utilizing a "square" shuttle tip; and

Fig. 4 shows a conventional shuttle tip construction after use.

In Figs. 1 and 2 I show my ball base shuttle tip 10 affixed to a conventional shuttle body 11 which is normally made of wood or fibre, or a combination thereof. My improved shuttle tip 10 is conical in shape having a flat base 12 and a circular rounded lower or trailing edge 13. The tip 10 is usually forged from a single piece of metal and has a pin or shank portion 14 by which it is affixed to the shuttle body 11. The shank 14 is normally forced into the bore or hole 15 at each end of the shuttle body 11 under great pressure and it is held in the body 11 by the helical serrations or threads 16 which are cut into the surface of the shank 14. Between the

2

base 12 and the shank 14 is a slightly depressed circular area 17 which is normally partially occupied by a fibre washer 18 that is positioned around the shank 14. The end portion 19 of the shuttle body 11 is rounded off at its edges 20 so that when the tip 10 is affixed to the body 11 even though the base 12 is flush against the end 19 a V-shaped area 21 is formed at the junction of the base tip 10 and the body 11.

10 In normal operation, as the shuttle moves through the warp the thread or filler 22 which is wound on a bobbin 23 is directed around a tension pin 24 through an opening in the shuttle body 11 and then over the inclined surface 25 of the shuttle body 11 and the shuttle tip 10. Due to the rounded edges 13 and 20, respectively, of the tip 10 and the shuttle body 11, there is no possibility of the thread 22 being caught and broken at this point, nor can the base 12 of the tip 10 catch on the warp thread as the shuttle moves forward and backward during the weaving operation. Therefore, the thread 22 will be guided over these rounded edges 13 and 20, respectively, resulting in a smooth weaving operation without any interruptions.

15 In Fig. 3 I show a modification of my conical tip 10 having the same improvements, namely, the rounded edges of the base portion. The tip 30 is known as a square tip which is utilized on some shuttles and which may also be constructed with rounded edges on its base.

20 In Fig. 4 I show the conventional shuttle tip 40 affixed to the shuttle body 11. In the conventional construction, the tip 40 is affixed to the shuttle body 11 with its base 41 flush against and abutting the end 19 of the shuttle 11. When the shuttle is new the juncture or abutting line between the metal tip 40 and the shuttle body 11 is smooth and even and in the beginning the thread 22 passes over this joint without any interruption. However, due to various conditions such as the excessive room temperature of the mills and the speed at which the shuttle is operated, the wood or fibre body of the shuttle contracts at the point where the tip is affixed to the body. This causes the sharp base 41 of the tip 40 to extend above the inclined surface 25 of the shuttle body 11 resulting in the thread 22 and the warp threads being caught and broken on this sharp base as the shuttle moves back and forth. In order to keep the breaks in the thread at a minimum, the shuttle tips are filed down from time to time to make a smooth joint once again with the shuttle body. This not only 25 results in considerable maintenance work but ex-

cessive loss of time when the tip breaks the warp threads.

Due to my improved tip construction, the expansion and contraction of the end of the wooden shuttle take place where the end of the shuttle meets the base of the tip which is at the bottom of the V-shaped area 21. By restricting the expansion of the end of the wooden shuttle in this area, the joint never becomes roughened or frayed which prevents the tip from tearing the warp and also eliminates expensive maintenance work.

While the invention has been described in detail with respect to a present preferred form which it may assume, it is not to be limited to such details and form since many changes and modifications may be made in the invention without departing from the spirit and scope of the invention in its broadest aspects. Hence, it is desired to cover any and all forms and modifications of the invention which may come within the language or scope of any one or more of the appended claims.

I claim:

1. A shuttle tip having a trailing peripheral edge rounded throughout for the purpose of eliminating thread breakage during a weaving operation.

2. A conical shaped shuttle tip having a circular trailing peripheral edge rounded throughout for the purpose of eliminating thread breakage during a weaving operation.

3. In a shuttle, a non-metallic body having a metal tip at each end, the edges of said body and tip being rounded at the juncture of the tip with the body for the purpose of eliminating thread breakage during a weaving operation.

4. In a shuttle, a body having a tip at each end, the edges of said body and tip being rounded at the juncture of the tip with the body.

5. In a shuttle, a non-metallic body having a conical shaped metal tip at each end, the edges of said body and tip being rounded at the juncture of the tip with the body for the purpose of eliminating breakage during a weaving operation.
